UNITED STATES PATENT OFFICE.

HENRY JAHR, OF ARDMORE, PENNSYLVANIA.

INSECT-DESTROYER.

1,204,777.

Specification of Letters Patent. Patented Nov. 14, 1916.

Application filed May 8, 1916. Serial No. 96,218.

To all whom it may concern:

Be it known that I, HENRY JAHR, a citizen of the United States, residing at Ardmore, in the county of Montgomery, State of Pennsylvania, have invented certain new and useful Improvements in Insect-Destroyers; and I do hereby declare the following to be a full, clear, and exact description of the invention, such as will enable others skilled in the art to which it appertains to make and use the same.

This invention relates to insect destroyers of the type commonly known as "fly swatters".

15 One object of the invention is to provide an improved form of such device which is adapted especially for use in killing flies when the latter are resting on the ceiling of a room.

20 Another object is to provide an improved form of device of this character which may be operated by one hand.

25 With the above and other objects in view, as will be hereinafter apparent the invention consists in general of certain novel details of construction and combinations of parts hereinafter fully described, illustrated in the accompanying drawing, and specifically claimed.

30 In the accompanying drawing, like characters of reference indicate like parts in the several views, and Figure 1 is a perspective view of the device ready for use; Fig. 2 is an enlarged side elevation partly 35 broken away showing the device in full lines in one position and in dotted lines in the second position; Fig. 3 is an enlarged detail section taken longitudinally through the handle of the device, certain parts of the 40 device being broken away; Fig. 4 is a detail of the slotted portion of the handle with the remainder of the handle covering this slotted portion removed.

45 In carrying out the objects of the invention there is provided a handle 10 which has extending longitudinally thereof an opening 11 which terminates in spaced relation to the lower or grip end of the handle. This handle is preferably formed in two 50 pieces united on the longitudinal plane so that the opening referred to may be readily formed. The handle is also provided with a transverse slot 12 wherewith the terminal end of the opening communicates and this 55 transverse slot 12 has extending from the opening a groove 13, the slot and groove

communicating with the notch 14 at the lower end of the slot, the notch being formed in one of the walls of the slot and having an opening 15 leading outward therefrom through the sides of the handle. Movably mounted in this opening is a pin 16 to which is fixed one end of a spring 17, the other end of said spring being secured to the handle. This spring normally holds the pin 65 outwardly disposed but pressure on the outer end of the pin will bend the spring and force the pin into the notch.

70 Mounted on the upper end of the handle 10 is a casing or ferrule 18 and between one side of this casing or ferrule is secured one end 19 of a leaf spring 20 which is bowed laterally as at 21 intermediate its ends and has its terminal free end extending across the mouth of the opening 11 in spaced relation thereto. Slidably mounted in the opening 11 is a rod 22, the rod projecting from the end of the opening toward the terminal portion of the leaf spring and having its lower end extending into the 80 slot 12 where it is provided with a cross member 23, the ends of which extend outward through the sides of the slot to form finger grips. A link 24 connects the upper end of the rod 22 with the spring 20 85 and on the terminal free end of the spring is mounted a striking member 25 preferably consisting of an oval piece of woven wire screen having a bending and reinforcing means 26 around its edge. 90

95 In operation, the spring 20 has its ends brought toward each other to stress the spring by pulling downward on the cross bar 23. This cross bar is then engaged in the notch 14 and the device is ready for use. When a fly is observed on the ceiling, the striking member is positioned below the fly and to within two or three inches thereof. The pin 16 is pressed inward with the thumb of the hand holding the device and this forces the cross bar out of the notch and therefore releases the rod. The spring 20, being under stress, throws the free end away from the fixed end and causes the striking member to engage that portion of the ceiling whereon the fly is resting thus 100 killing the latter.

105 There has thus been provided a simple and efficient device of the kind described and for the purpose specified.

110 It is obvious that many minor changes may be made in the form and construction

of the invention without departing from the material principles thereof. It is not therefore desired to confine the invention to the exact form herein shown and described but it is wished to include all such as properly come within the scope claimed.

Having thus described the invention, what is claimed as new, is:—

1. A fly swatter including an elongated handle having an opening extending longitudinally from one end and terminating in spaced relation to the other end, a spring fixed to the handle and bowed laterally to extend across the open end of the handle, a rod slidable in the opening and having connection with the opening, a striking member carried by the free end of the spring, and a latch and trigger mechanism at the inner end of the opening to releasably hold the rod inward and the spring under stress.
2. A fly swatter including an elongated handle having an opening extending longitudinally thereof and terminating in spaced

relation to the other end of the handle, the handle being provided with a transverse slot wherewith the terminal end of the opening communicates, one wall of the slot being provided with a notch and having an opening leading outward therefrom through the handle, a pin movable in the last-mentioned opening, a spring yieldably holding the pin outward, a rod slidable in the longitudinal opening and projecting from the end thereof, a cross bar on the rod movable in the slot and engageable in the notches, a leaf spring fixed to the handle and bowed laterally to extend across the end of the handle in spaced relation thereto, a link connecting the rod and spring, and a striking member carried by the free end of the spring.

In testimony whereof, I affix my signature, in the presence of two witnesses.

HENRY JAHR.
